HAND MAGNIFIER

St. Barth Alaska, 3811 Scoville Ave.,
Berwyn, Ill. 60402

Filed Dec. 18, 1968, Ser. No. 15,041

Term of patent 14 years

Int. Cl. D16—08

U.S. Cl. D57—1

FIG. 1

FIG. 4

FIG. 3

FIG. 2

FIG. 1 is a perspective view of a hand magnifier showing my new design;

FIG. 2 is a top plan view thereof;

FIG. 3 is a bottom plan view thereof; and

FIG. 4 is a cross-section taken on line 4—4 of FIG. 1. Specifications for the achromatic lens are so the slit focus of the achromatic lens will permit the reading materials to be placed flat against the bottom of the cone, and light can enter the cone through the clear side walls of the cone. The slit is held close to the eye or against eyeglasses of reader.

I claim:

The ornamental design for a hand magnifier, as shown.
